(57) CLAIM

The ornamental design for a wall mountable tray for hand cleaner bottle, as shown and described.

DESCRIPTION

FIG. 1 is a perspective view of a wall mountable tray for a hand cleaner bottle showing my design;

FIG. 2 is a front view thereof;

FIG. 3 is a rear view thereof;

FIG. 4 is a top view thereof;

FIG. 5 is a bottom view thereof;

FIG. 6 is a right side view thereof; the left side view being a mirror image thereof; and,

FIG. 7 is an exemplary view thereof showing a state in use with the hand cleaner bottle being set.

In the drawings, the broken lines depict environmental subject matter only and form no part of the claimed design.

1 Claim, 7 Drawing Sheets
